UNITED STATES PATENT OFFICE.

HOMER C. BOSTIAN, OF LYONS, NEW YORK.

RULE-HOLDER.

1,275,835.

Specification of Letters Patent. Patented Aug. 13, 1918.

Application filed November 3, 1917. Serial No. 200,168.

To all whom it may concern:

Be it known that I, HOMER C. BOSTIAN, a citizen of the United States, residing at Lyons, in the county of Wayne and State of New York, have invented new and useful Improvements in Rule-Holders, of which the following is a specification.

This invention relates to rule holders adapted to be applied to the pocket of a garment and it consists in the novel features hereinafter described and claimed.

An object of the invention is to provide a holder of the character stated of simple and durable structure and which may be easily and quickly applied to the pocket of a garment and having its parts so arranged that the major portion of the holder is located within the pocket.

With this object in view the holder comprises a plate of spring metal bent upon itself and having one side portion adapted to fit against the inner surface of the pocket and the other side portion adapted to lie against the outer surface thereof with teeth provided upon the outer portion for engaging the material of the garment. A flexible band of rubber or other suitable material is attached to the inner portion of the said plate by means of eyelets which pass transversely through the said band and the said plate. The eyelets are opposite the teeth and the points of the teeth may be received in the eyelets when the device is applied. The said band is located within the pocket when the device is applied to a garment and is adapted to receive a rule whereby the rule is prevented from falling from the pocket of the garment in the event that the wearer should assume a stooping posture or at other times.

In the accompanying drawings:

Figure 1 is a side elevation of a portion of a garment showing the rule holder applied;

Fig. 2 is a vertical sectional view of the same.

Fig. 3 is a detailed perspective view of the rule holder.

The rule holder comprises a plate 1 of spring metal which is bent upon itself and one side portion of the said plate is provided at its opposite edges with inwardly disposed teeth 2. A band 3 of rubber or other suitable elastic material is applied to the surface of one side portion of the plate 1 and a metallic plate 4 is located at the inner

surface of the side of the band 3. Eyelets 5 pass transversely through the inner portion of the plate 1, the adjacent portion of the band 3 and the plate 4 and serve as means for securing the said parts together. The said eyelets 5 are in alinement with the teeth 2 and the points of the said teeth may be received with the said eyelets. The band 3 is provided at its inner side and at its upper edge with an extension 6 which is disposed above the upper portion of the plate 1.

When the device is applied the inner part of the plate 1 is inserted in the pocket of a garment consequently the plate 4 and the lower portion of the band 3 are positioned in the pocket. The outer portion of the plate 1 extends along the outer surface of the pocket of the garment and the teeth penetrate the material of the garment and the points of the said teeth may be housed in the eyelets 5. Thus the holder is effectually secured in position upon the garment. The rule is slipped endwise into the band 3, the extension 6 serving as a guide for directing the end of the rule into the band. In view of the fact that the band 3 is of flexible material, it will securely grasp the rule and prevent the same from accidentally falling from the pocket. When it is desired to withdraw the rule considerable force is applied to the same and the rule is pulled out of the band 3.

From the foregoing description taken in connection with the accompanying drawing, it will be seen that a rule holder of simple and durable structure is provided and that the same may be easily and quickly applied to the pocket of a garment or easily removed therefrom.

Having described the invention what is claimed is:

1. A rule holder comprising a plate of elastic metal bent upon itself and having at the edges of one side portion inwardly disposed teeth and an elastic band applied to the side of the said plate, and eyelets passing transversely through the plate and the band and adapted to receive the points of the teeth.

2. A rule holder comprising a metallic resilient plate bent upon itself, one side portion of the plate being provided at its edges with inwardly disposed teeth, an elastic band applied to the side of the plate and having at its inner portion an upwardly disposed extension, eyelets passing transversely

through the plate and the band and adapted to receive the points of the teeth.

3. A rule holder comprising a resilient metallic plate bent upon itself and having at the edges of one side portion inwardly disposed teeth, an elastic band applied to the opposite side portion of said plate, a metal-

lic plate located against the inner surface of said band eyelets passing through the said plate and the band and adapted to receive the points of the teeth.

In testimony whereof I affix my signature.

HOMER C. BOSTIAN.
